UNITED STATES PATENT OFFICE

2,637,790

ELECTRIC OUTLET SOCKET

Charles E. Woodside, Spokane, and Wilbur R. Smith, Colfax, Wash., and Albert L. Woodside, Butte, Mont., and Zenas A. Armstrong, Spokane, Wash.

Original application October 23, 1948, Serial No. 56,072. Divided and this application November 20, 1950, Serial No. 196,578

2 Claims. (Cl. 200—51.13)

1

This invention relates to an electric outlet socket and the present application constitutes a division from the copending application filed October 23, 1948, and having Ser. No. 56,072, now Patent No. 2,562,592, July 31, 1951.

One object of the invention is to provide a socket which may be connected with conductor wires extending from a ceiling and used as a drop light.

Another object of the invention is to provide a socket of such construction that a shell for receiving a terminal plug may be turned from a position in which a circuit is completed to a position for breaking the circuit and thus allow the circuit to be broken when a plug is removed and eliminate danger of a person receiving an electric shock by accidentally thrusting a finger into a socket from which a plug has been removed.

Another object of the invention is to so form the socket that it may have associated with it a key for effecting movement of a movable contact into and out of engagement with a stationary contact.

Another object of the invention is to provide a socket of this character which is easy to assemble or take apart and will not be liable to get out of order.

The invention is illustrated in the accompanying drawings wherein:

Fig. 1 is a sectional view taken longitudinally through the socket.

Fig. 2 is a sectional view taken transversely through the socket along the line 2—2 of Figure 1.

Fig. 3 is a view similar to Figure 1 showing a modified construction wherein the switch is omitted.

Fig. 4 is a perspective view of a sleeve which is rotatably mounted in the socket.

Fig. 5 is a view of a plug used with the socket.

This socket has a housing 1 or shell formed of insulation and about its lower end the housing is formed with a circumferentially extending inwardly projecting flange 2 defining a central opening 3 and having its under or outer surface 4 beveled to form a guide for directing a plug through the opening 3.

An insert or socket 5 formed of insulation fits into the housing through the open upper end thereof with its annular wall spaced from the annular wall of the housing, thus providing space 6 in the housing about the socket. At its upper end the socket is surrounded by a collar 7 which is threaded and screwed into the internally

threaded upper end portion of the housing, the collar being of such thickness that when the lower end of the socket is bearing against the inner surface of the flange 2 the upper portion of the collar projects upwardly from the shell. Therefore a cap 8 may be screwed upon the protruding upper portion of the collar. This cap is formed at its center with an opening 9 through which pass the drop cord wires 10. Within the socket 5 fits a sleeve 11 which is also formed of insulation and at its lower end rests upon the flange 2. The annular wall of the sleeve is formed with diametrically opposed slots 12 which lead from the lower end of the sleeve and register 15 with recesses or notches 13 formed in the marginal edge of the flange in diametrically opposed relation to each other. The slots 12 communicate with openings 14 formed through the wall of the socket 5 and extending circumferentially thereof, and into the openings 14 project free end portions of resilient contact strips 15. These contact strips extend circumferentially of the socket in grooves 16 and are secured by screws, free ends of the contact strips being bent to form seats 18 into which fit contacts 19 projecting from opposite sides of a plug 20.

The plug is circular in cross section and is thrust into the sleeve through the opening 3 with its contacts passing through the notches 13 and the slots 12 and into the openings 14. When turning movement is imparted to the plug, the sleeve turns with it and outer ends of the contacts 19 move along inner surfaces of the contacts 15 and into the seats 18. Therefore current will be conducted to the center contact 21 and the shell 22 of the plug and a bulb screwed into the shell will be lighted. When the bulb is turned in a direction to unscrew it from the shell, the sleeve may be turned with it to move contacts 19 away from contacts 15 to break the circuit. Instead of providing the plug 20 with a center contact and a shell for reception of a bulb the plug may be of such construction that the prongs of a terminal plug for an extension cord may be thrust into engagement with comparison contacts of the plug 20.

In order to releasably hold the sleeve in the position shown in Figure 2 with the contacts of the inserted plug out of engagement with the contact strips 15 there has been provided a latch strip 23 formed of resilient metal. This latch strip is bowed longitudinally and fits into a groove 24 formed in the end wall 25 of the sleeve 11. This groove extends diametrically of the sleeve and ends of the latch strip project from

the groove and engage in recesses 26 formed in the socket. The latch strip serves to prevent turning of the shell when in its normal position and as its intermediate portion extends across an opening 27 formed centrally of the head 25 of the sleeve, a pin or bar 38 projecting from the inner end of the plug 20 may engage the latch strip and force it out of the groove when the plug is thrust into the sleeve and its bars moved through the opening 27. It will thus be seen that the sleeve will be held stationary when the plug is removed and an electric shock will not be received if a finger is thrust into the socket of the plug from which a bulb has been removed.

One of the drop-cord wires 10 is passed downwardly through the opening 28 in the upper portion of the socket and is attached to the adjacent screw 17. The other drop cord wire is connected with a screw 29 carried by a stationary contact 30 which is partially embedded in the upper portion of the socket and projects into a pocket 31 leading from the upper end thereof. A movable contact 32 formed of resilient metal is secured at one end by the other screw 17 and extends upwardly along the socket; the upper portion of the strip from which the movable contact is formed being bent so that it extends into the pocket and has its free end disposed under the stationary contact. The movable contact is biased towards the stationary contact and in order to permit a circuit to be broken by separation of the contacts there has been provided a key 33 having its stem 34 rotatably mounted through an opening 35 in the wall of the housing or shell 1 and engaged with a shaft 36 carrying a cam disk 37. The cam disk is located over the movable contact and by turning the key the shaft will be rotated and the cam will press the movable contact away from the stationary contact and break the circuit. Therefore a bulb screwed into the socket 22 of the plug may be lighted or extinguished by means of the key but when the bulb is removed an electric shock can not be accidentally received as the contacts 19 are moved out of engagement with contacts 15 during removal of the bulb.

The socket shown in Figure 3 is of a somewhat different construction from that illustrated in Figure 1 but certain of its elements are of the same construction and these elements are designated by the same reference numbers. This socket is shorter than that shown in Figure 1, and the drop cord wires are both connected with screws 17, the stationary contact and the comparison movable contact and actuating key being omitted. It is therefore not necessary to provide a pocket in the upper portion of the socket 5 and this socket and the shell may be of reduced length. It is, however, necessary to form the upper portion of the socket with a second opening 28' to receive the second wire 10. In this embodiment of the invention closing of the circuit is only accomplished by turning of the sleeve 11 and consequent movement of the contacts 19 of an inserted plug into engagement with the contact strips 15.

Having thus described the invention, what is claimed is:

1. A power outlet comprising a body of insulation formed with a socket open at its lower end, contacts carried by the body at opposite sides of

the socket and having portions exposed through side openings in the wall of the socket, a sleeve in said socket rotatable therein and being open at its lower end and near its upper end formed with side openings movable into and out of position to register with the side openings of the socket by turning movement of the sleeve in the socket, a shell removably mounted about the body and having an inwardly projecting annular flange about its lower end overlapping walls of the socket and the sleeve and rotatably holding the sleeve in the socket, said body having its upper portion formed with a pocket located above the socket and open at its upper end, a stationary contact in said pocket adapted to have a power wire connected thereto, a movable contact strip leading from one contact of the body into the pocket and overlapped by the stationary contact and normally engaging the stationary contact, and the other contact carried by the body being adapted to have a power wire attached to it.

2. A power outlet comprising a body of insulation formed with a socket open at its lower end, contacts carried by said body at opposite sides of the upper portion of said socket, a sleeve in said socket open at its lower end for reception of a plug provided with contacts engageable with the contacts carried by the body when the plug is fitted into the sleeve, a shell removably mounted about said socket and at its lower end having an inwardly projecting flange overlapping lower ends of walls of the socket and the sleeve, said body being formed above the socket with a pocket having an open upper end, a stationary contact in said pocket adapted to have a power wire connected with it, one of the contacts at opposite side of the socket being also adapted to have a power wire connected with it, the upper portion of the body at one side of the pocket being formed, with a passage for reception of the last mentioned power wire, a movable contact consisting of a strip of resilient metal connected with the contact at the other side of the socket and extending upwardly along the outer surface of the socket, with its upper portion passing into the lower portion of the pocket and overlapped by the stationary contact and movable into and out of engagement with the stationary contact, and a cap removably threaded to the upper end of the body above the shell in covering relation to the pocket and formed with a passage for the said power wires.
